UNITED STATES PATENT OFFICE.

WASILY KOUZNEZOFF, OF MOSCOW, RUSSIA.

HOT-WATER ACCUMULATOR.

SPECIFICATION forming part of Letters Patent No. 593,418, dated November 9, 1897.

Application filed March 22, 1897. Serial No. 628,659. (No model.)

To all whom it may concern:

Be it known that I, WASILY KOUZNEZOFF, a subject of the Czar of Russia, residing at Moscow, in the Empire of Russia, have invented certain new and useful Improvements 5 in Hot-Water Accumulators for Locomotives, of which the following is a specification.

My invention has relation to apparatus for increasing the working capacity of a locomotive to enable the same to perform its work with greater certainty or regularity and with less consumption of fuel; and in such connection it relates particularly to the general construction and arrangement of the apparatus 15 for said purposes.

As practice has demonstrated, in the known type of six-wheeled locomotive it has not been possible to work it to its full extent or capacity nor to vary the load with any degree 20 of saving without considerable outlay and waste of the fuel in deriving the requisite power ordinarily required of present-day locomotives. The most practical manner of 25 remedying such defects as above mentioned at the present time is to replace such a locomotive by another of more modern type.

My invention has been designed and is so arranged that the working power of the locomotive can be greatly increased at nominal 30 expense, due to the employment of a simple and efficient form of apparatus in conjunction therewith to insure a greater capacity or power being derived therefrom and in which it is possible to vary the load at will with a 35 great saving by the avoidance of much of the waste of fuel incident to the use of present-day locomotives.

My invention, stated in general terms, consists in providing a locomotive-boiler with a 40 hot-water accumulator and its accessories when constructed and arranged in connection with the boiler or with a tender at a convenient distance therefrom, substantially as hereinafter described and claimed.

The nature and scope of my invention will 45 be more fully understood from the following description, taken in connection with the accompanying drawings, forming part hereof, in which—

Figure 1 is a sectional view of an apparatus 50 embodying main features of my invention in application to a locomotive-boiler of the type

hereinbefore explained, and Fig. 2 is a rear elevational view of said apparatus.

Referring to the drawings, A is a reservoir or accumulator, which is suitably located about or above the boiler B, or the same may, if desired, be located in connection with a tender (not shown) to be connected with the locomotive, the accumulator being connected 55 with the boiler or tender by pipes or tubes a, b, and c. These pipes or tubes may be differently arranged, if desired, so as to correspond with any alteration with respect to position of the accumulator A and are closed or opened 60 by means of cocks a', b', or c'. The pipe or tube b is led from the accumulator into the boiler B and below the water-level therein, while the tube or pipe c connects the accumulator A with the dome C of the engine or with 65 the steam-space of the boiler in its upper part thereof and the tube a of the accumulator A, with a pipe x, provided with a valve y, with one of the injectors D. Of course it will be understood that my invention is not limited 70 to the use of a single accumulator, as more than one may be employed with good results.

The mode of operation of an apparatus of my invention is as follows: When the locomotive comes to a stop at a station or on a siding, the cock a' is opened, so that the injector D may blow out any air in the accumulator A, or when the locomotive is in transit, in which only a certain amount of steam is required, the cock a' is opened, so that 85 steam may be conducted to the injector D by the pipes a and x and water forced or pumped into the boiler B. The cock b' is then gradually opened, so that water can pass from the boiler B to the reservoir or accumulator A, 90 and when the steam has begun to issue from the injector D the cock a' is closed again, as the air has by this time been removed from the accumulator A. In this manner the steam in the accumulator A is utilized to fill the 95 boiler B with water by means of the injector D and is not uselessly blown into the atmosphere. After sufficient water has been led from the boiler to the accumulator, the level of which can be observed by means of the 100 water-gage d, the cock b' is then closed and the cock c' is opened, so as to let steam into the accumulator A. The cock c' remains open until the accumulator is emptied of its water

into the boiler B. The locomotive in traveling up gradients or inclines, when the water-level in the boiler falls to the lowest limit the cock b' is opened until sufficient heated water passes from the accumulator A into the boiler to raise the water-level in the latter to the necessary height, and when the top of the gradient or incline has been reached the said water-level in the boiler will be kept at the height required by means of the injector after the cock b' has been closed. The filling of the accumulator A with water is then effected as before—that is, the cock c' is shut off, the cock a' is opened, and as soon as the steam begins to issue from the injector the cock a' is closed and the cock b' is opened, and when there is sufficient water in the accumulator A the cock b' is also closed and the cock c' is opened. The steam passing from the pipe a can be used for feeding the boiler by means of the injector and also for heating the water in the tender.

From the foregoing description it will be evident that the apparatus not only supplies heated water when most required without undue expense with respect to the heating of the same up to a temperature corresponding to ordinary steam-pressure, but it also prevents waste of steam in the working of the

injector to feed the boiler from the tender or other source. The volume of water in the accumulator represents the difference between the highest and lowest limit of water-level in the boiler, and the effect of the accumulator is therefore to double the working power of the water.

Having thus described the nature and objects of my invention, what I claim as new, and desire to secure by Letters Patent, is—

The combination with a locomotive-engine having a boiler, a dome and an injector, of an accumulator or reservoir A, and pipes a, b and c, provided with stop-cocks, the pipe b, from said accumulator being connected with said boiler below the water-level therein, the pipe c, from said accumulator being connected with said dome or steam-space of said boiler and the pipe a, from said accumulator being connected by means of a pipe x, with said injector, substantially as and for the purposes described.

In testimony whereof I have hereunto set my signature in the presence of two subscribing witnesses.

WASILY KOUZNEZOFF.
